UNITED STATES PATENT OFFICE

2,516,938

MECHANICAL PENCIL WITH SCREW FEED

Francis M. Aimes, Malden Bridge, N. Y.

Application February 10, 1950, Serial No. 143,431

6 Claims. (Cl. 120—18)

1

This invention relates to what are generally referred to as "mechanical pencils." More particularly, the invention deals with devices of this type and kind having a simple and economical screw mechanism for the positive feeding of a lead in forward and reverse directions, whereby the device can be produced and sold at a very nominal cost and, at the same time, a strong, durable and long-lasting device is provided.

The novel features of the invention will be best understood from the following descriptions, when taken together with the accompanying drawing, in which certain embodiments of the invention are disclosed and, in which, the separate parts are designated by suitable reference characters in each of the views and, in which:

Fig. 1 is a side and sectional view of a pencil made according to my invention diagrammatically illustrating a lead in extended position for use.

Fig. 2 is an enlarged section on the line 2—2 of Fig. 1.

Fig. 3 is a view similar to Fig. 1 showing another form of construction; and

Fig. 4 is an enlarged section on the line 4—4 of Fig. 3.

In Fig. 1 of the drawing, I have shown a pencil comprising a contracted and more or less bullet-shaped tip end 10, an elongated tubular barrel 11 and a feed plunger 12. The barrel 11 has an inwardly spun or fashioned flange end 13 engaging the groove 14 in the tip 10.

The feed plunger 12 has a spiral feed groove 15 engaged by two or more inwardly-pressed key-beads 16 on the barrel 11 to control feed of the plunger 12 by rotation of the barrel with respect to the tip.

Extending from what might be termed the lower end of the barrel, centrally thereof, is a rectangular rod 17 which fits in a corresponding rectangular portion 18 of the bore 19 of the tip 10. At the end of the rod 18 is a spring clip portion 20 for engaging a lead 21 to provide frictional or positive feeding of the lead in the tip 10; the bore 19 of the tip 10 has a reduced guide bore 22 at its contracted end for support and slight frictional engagement with the lead 21, this end of the section being split in accordance with the sectional view of Fig. 4, the latter being specifically applied to Fig. 3, but the tip portion of both forms of pencils shown is, in this respect, the same.

Considering now Fig. 3 of the drawing, here is shown a tip 10', generally similar to the tip

2

10, and at 11' is shown a barrel, the barrel being coupled with the tip 10' through an intermediate sleeve 23 having a key-engagement with the tip 10' as at 24 for free rotation thereon.

5 The inner end of the sleeve 23, beyond the limits of the tip 10', has an enlarged internally threaded nut portion 25, upon which the barrel 11' has a pressed or other firm mounting, so that the sleeve 23 and barrel 11' will operate as one unit. The bore 19' of the tip 10' is also of rectangular cross-sectional form to key itself with a rectangular rod 26 which differs from the rod 17 primarily in being of larger diameter and having corner portions of the rods fashioned to form 15 thread sections 27 for operative engagement with the threads of the nut 25, so as to feed the bar 26 longitudinally of the tip 10' in expelling and repelling the lead which is mounted on the clip 28, similar to the clip 20. The lead is not shown in 20 Fig. 3.

The tip 10' has a small bore end 22', similar to the bore 22 and, as seen at 29 in Fig. 4 of the drawing, the contracted end of the tip is split so as to provide slight spring properties to this 25 end for supporting engagement with the lead and to compensate for slight variances in diameters of the lead.

In both forms of the construction shown, the lead is positively extended or retracted by rotation of the tip and barrel or the sleeve 23 as in 30 Fig. 1, one with respect to the other.

From a standpoint of description, the complete mechanical pencil can be said to comprise a tip end and a barrel end with a plunger moved 35 positively in both directions axially of the tip and barrel in the feed of a lead supported thereon. In this connection, the rod 26 of Fig. 3 is the plunger, as is also the rod end 17 of the plunger 12. In Fig. 1, the enlarged portion of the plunger 40 has a screw thread or screw feed engagement directly with the barrel, whereas in Fig. 3, this engagement is with the nut portion of the sleeve which is fixed to the barrel.

Having fully described my invention, what I 45 claim as new and desire to secure by Letters Patent is:

1. A mechanical pencil of the character described, comprising a barrel part and a tip end 50 mounted in and movable longitudinally of said barrel and tip, said tip having a rectangular bore, the plunger having a rectangular portion engaging the rectangular bore in the tip to key the tip and rectangular portion of the plunger 55 against relative rotation, means for frictionally

supporting a lead on the rectangular portion of said plunger, the tip having a contracted reduced bore-end through which a lead is adapted to pass, and cooperating means on the barrel and plunger providing longitudinal movement of the plunger axially of said tip upon relative rotation of the barrel and the tip.

2. A mechanical pencil of the character described, comprising a barrel part and a tip end rotatably coupled with the barrel, a plunger mounted in and movable longitudinally of said barrel and tip, said tip having a rectangular bore, the plunger having a rectangular portion engaging the rectangular bore in the tip to key the tip and rectangular portion of the plunger against relative rotation, means for frictionally supporting a lead on the rectangular portion of said plunger, the tip having a contracted reduced bore-end through which a lead is adapted to pass, cooperating means on the barrel and plunger providing longitudinal movement of the plunger axially of said tip upon relative rotation of the barrel and tip, and said last named means comprising a spiral groove on the plunger and an indentation on the barrel operatively engaging said groove.

3. A mechanical pencil of the character described, comprising a barrel part and a tip end rotatably coupled with the barrel, a plunger mounted in and movable longitudinally of said barrel and tip, said tip having a rectangular bore, the plunger having a rectangular portion engaging the rectangular bore in the tip to key the tip and rectangular portion of the plunger against relative rotation, means for frictionally supporting a lead on the rectangular portion of said plunger, the tip having a contracted reduced bore-end through which a lead is adapted to pass, cooperating means on the barrel and plunger providing longitudinal movement of the plunger axially of said tip upon relative rotation of the barrel and tip, and said last named means comprising a nut portion on the barrel, and thread sections on said plunger operatively engaging said nut portion.

4. A mechanical pencil of the character described, comprising a barrel part and a tip end rotatably coupled with the barrel, a plunger mounted in and movable longitudinally of said barrel and tip, said tip having a rectangular bore, the plunger having a rectangular portion engag-

ing the rectangular bore in the tip to key the tip and rectangular portion of the plunger against relative rotation, means for frictionally supporting a lead on the rectangular portion of said plunger, the tip having a contracted reduced bore-end through which a lead is adapted to pass, cooperating means on the barrel and plunger providing longitudinal movement of the plunger axially of said tip upon relative rotation of the barrel and tip, said last named means comprising a nut portion on the barrel, thread sections on said plunger operatively engaging said nut portion, and said nut portion constituting part of a sleeve interposed between the barrel and said tip.

5. A mechanical pencil of the character described, comprising a barrel part and a tip end rotatably coupled with the barrel, a plunger mounted in and movable longitudinally of said barrel and tip, said tip having a rectangular bore, the plunger having a rectangular portion engaging the rectangular bore in the tip to key the tip and rectangular portion of the plunger against relative rotation, means for frictionally supporting a lead on the rectangular portion of said plunger, the tip having a contracted reduced bore-end through which a lead is adapted to pass, cooperating means on the barrel and plunger providing longitudinal movement of the plunger axially of said tip upon relative rotation of the barrel and tip, and said contracted bore end of the tip being split.

6. A mechanical pencil of the character described, comprising a barrel part and a tip part having a contracted end, the tip part having a rectangular bore extending longitudinally throughout the major portion of the length thereof, said bore terminating at the contracted end of the tip in a small diameter lead guide bore, a plunger movable longitudinally of the barrel part, said plunger having a rectangular portion conforming with and fitting snugly in the bore of said tip to prevent relative rotary movement one with respect to the other, and cooperating means between the plunger and barrel for feeding the plunger longitudinally of the tip upon relative rotation of the tip and barrel.
